ATTORNEY

UNITED STATES PATENT OFFICE

CORNELIS BOL, OF HINDHOVEN, NETHERLANDS, ASSIGNOR TO RADIO CORPORATION OF AMERICA, A CORPORATION OF DELAWARE

ELECTRIC DISCHARGE TUBE

Application filed February 18, 1928, Serial No. 255,211, and in the Netherlands April 18, 1927.

The invention relates to electric discharge tubes, more particularly to those for use in installations for wireless telephony and telegraphy.

- 5 In the case of vacuum tubes it is known to mount the oscillation generator and the amplifier in a common vacuum. In such a system one single filament is utilized for the generator and the amplifier.
- 10 The discharge tube according to the invention comprises a plurality of mutually separated sets of grids with anodes pertaining thereto and a common equipotential cathode. The various systems are separated from one another by screening walls in order to prevent reaction of one system on another.
- 15 In addition to other advantages the use of an equipotential cathode affords with relation to the filament the further advantage that when use is made of a hollow cathode with a heating element, this combination can be used as a rectifier. This rectifier may then be used, for example, in anode voltage supply apparatus.
- 20 The invention will be more clearly understood by referring to the accompanying drawing which diagrammatically represents a discharge tube according to the invention. In the drawing, several electrode systems are mounted in a glass envelope 1. An equipotential cathode 2 which, according to this mode of execution, consists of a hollow tube which can be heated by radiation or by electron bombardment or in both manners by
- 25 means of a heating element 3. The outer surface of the tube is coated with a suitable material, for example, barium oxide.

The anodes of the various systems are denoted by 4, 5 and 6 and the grids by 7, 8 and 9, while 10 and 11 denote screening walls or shields which separate the various systems from one another. The combination of the 55 filament 3 with the hollow tube 2 is very suitable for use as a rectifier.

The electrode systems may be constructed as different stages in a receiving circuit-arrangement for wireless telegraphy or telephony, but it is also possible to use them in series-connection.

What I claim is:

1. An electron discharge tube comprising an envelope having mounted therein a single 65 tubular cathode, a single heating element within the cathode, a plurality of sets of electrodes, each set comprising an independent pair of concentric cylindrical input and output electrodes surrounding and coaxial with 70 said cathode and disposed end to end along said cathode to cooperate with distinct and separate lengths of said cathode, and a shielding disk between adjacent sets and extending 75 from the envelope to the cathode.

2. An electron discharge tube comprising an envelope having mounted therein a single equipotential cathode, a plurality of sets of electrodes arranged end to end and spaced longitudinally along the cathode, each set 80 comprising cylindrical input and output electrodes and each set disposed coaxially of said cathode to surround different and distinct lengths of said cathode, and shielding disks 85 between adjacent sets disposed transversely to the cathode.

CORNELIS BOL.
